UNITED STATES PATENT OFFICE.

VICTOR F. CARL, OF BROOKLINE, MASSACHUSETTS.

SOAP-PRESS AND PERFORATING-LABELER.

1,326,573.

Specification of Letters Patent. Patented Dec. 30, 1919.

Application filed February 19, 1917. Serial No. 149,449.

To all whom it may concern:

Be it known that I, VICTOR F. CARL, a citizen of the United States, and resident of Brookline, county of Norfolk, Commonwealth of Massachusetts, have invented an Improvement in Soap-Presses and Perforating-Labelers, of which the following description, in connection with the accompanying drawings, is a specification, like characters on the drawings representing like parts in each of the several views.

This invention relates to presses for forming and shaping cakes of soap or like relatively soft moldable material. According to present practice while it is customary among soap manufacturers to impress on all the cakes of soap constituting their output, a distinguishing trade-mark or trade-name, as well as usually the name of the manufacturer, heretofore such impression has been merely in relief on the surfaces of the cake or sometimes with the letters cut in, to a small depth. With this kind of marking however as soon as the cake of soap has been used a very little the impression is wholly obliterated so that there is nothing on the cake thereafter to identify it or its source of manufacture in any way. The prime object of the present invention is to provide means whereby cakes of soap or like material may be provided with a distinguishing trade-mark or trade-name or other means of identification that will be readily distinguishable and conspicuous until the cake is entirely consumed. To this end I provide an improved press mechanism having associated therewith perforating devices operative preferably from both sides of the cake to cut through to approximately the median plane of the cake the desired distinguishing trade-name or other characterizing mark, and in conjunction therewith provide means for injecting into such cut out letter recesses a quantity of soap in a relatively fluid condition and of a color contrasting with that of the soap of the cake so that upon the solidification of such injected differently colored soap, a permanent distinguishing trade-mark or name is produced extending from the surface of the cake into the median plane thereof. The invention is shown as embodied in a turret type of press mechanism wherein the cakes are automatically transferred to successive stations, and while in its more comprehensive embodiment as herein described, the in-

vention contemplates the perforating of the cakes and the injection of liquid soap in the cut out perforations to constitute the distinguishing trade-name or mark, the turret press mechanism to be described may also be used for pressing and forming the cakes to a finished shape only, if desired. The foregoing and other objects and advantages of the invention will more fully appear from the following detailed description, and the distinctive features of novelty will be pointed out in the appended claims.

Referring to the drawings:

Figure 1 is a front view of the machine embodying the invention;

Fig. 2 is a side view thereof;

Fig. 3 is a horizontal section on line 3—3 of Fig. 2;

Fig. 4 is an enlarged fragmentary detail in horizontal section and showing a plan view of the second station of the press at which the liquid soap is introduced;

Fig. 5 is a fragmentary detail perspective of one pair of the pressing and perforating dies;

Fig. 6 is a fragmentary sectional plan showing the locking device for the turret, on line 6—6 of Fig. 2;

Fig. 7 is a fragmentary side view partly broken away in section showing the second or soap injecting station of the press;

Fig. 8 is a plan view showing the cake of soap as it appears after leaving the first station, *i.e.*, after the first pressing operation and with its inclosing box; and

Fig. 9 is a side view of the finished cake.

The frame work of the machine comprises a base 1, a set of upright standards 2, and an overhead frame portion 3. To the base 1 and overhead frame portion 3 are secured opposite brackets 4, 4 and in these is fixed an upright column 5 which holds for rotation a turret 6. The turret 6 is formed with a series of spaced apart seats 7 to receive boxes 8, these boxes being shown as rectangular in form and constituting soap holders in the pressing operation. Any suitable number of these seats 7 and holding boxes 8 may be provided in the turret, four of these being shown, this number corresponding with the number of stations for the operations to be described and the turret being rotated with an intermittent movement a quarter turn at each step. Any suitable means may be provided for imparting this rotation to the turret but as shown it

is provided with a toothed periphery 9, the teeth being shown as ordinary gear teeth which are engaged at intervals by the teeth of a mutilated gear 10 fixed on an upright shaft 11 journaled at its ends in suitable sleeve bearings secured to the frame members 1, 3. The shaft 11 has a gear 12 fixed thereon which in turn is driven by a pinion 13 fixed on an upright shaft 14 journaled 10 at its ends in the frame members 1, 3, this shaft having fixed thereon a drive pulley 15 and constituting the prime drive shaft of the machine. It will be understood that the mutilated gear 12 will be provided with 15 series of teeth sufficient in extent to turn the turret 6 a one quarter revolution at each movement thereof, with alternating blank space allowing the turret an intervening dwell between movements for the operations 20 to be described. For stopping the turret and holding it in definite position at these successive dwells it is provided with a series of stop projections 16 engageable by a stop bar 17 which is pivoted at 18 to a horizontal 25 member 19 of the frame work, this stop bar projecting beyond its pivot point as shown at 17^a to constitute a lever, the extremity of which is provided with a roll 20 engageable by a face cam 21 fixed to the shaft 11, the configuration of this cam being such as to cause the bar 17 to be swung downward just as the turret comes to the end of one of its intermittent movements, and permitting said bar to swing up under 30 the action of a spring 22 just before the teeth of the mutilated gear 12 engage the teeth of the turret to start the rotation thereof.

Each of the soap holders 8 which are fitted 40 in the turret seat 7 may be of a size to hold any desired number and size of cakes to be handled by the machine. As shown each holder 8 is adapted to receive two cakes of soap, for this purpose being divided 45 into two compartments by a partition 8^a. The holders 8 and the compartments into which they are divided are as shown rectangular in shape and the holders are open at top and bottom to permit the operation 50 of the forming dies to be presently described, the holders engaging only edge portions of the soap cake as will be better understood later. The forming dies to act upon the soap cake from top and bottom 55 are carried by die heads, the upper head being indicated at 23 and the lower die head 24. These die heads are periodically moved toward each other for shaping the soap cakes, each die head having for this purpose 60 similar operating mechanism consisting in a cam 25 fixed on a shaft 26 suitably journaled in bracket mountings 27 of the frame, these shafts being rotated by a chain and sprocket drive 28 from a shaft 29, journaled in a suitable bracket bearing 30

of the frame and driven by spiral gearing 31 from the shaft 11. The lower die head 24 will be held against its cam 25 by gravity while suitable tension springs 32 anchored to the frame are provided for holding the upper die head 23 against its cam. The forming dies 33 which are carried at the ends of radial arms of the die heads 23, 24 are set in position to register with the compartments of the holders 8 when the turret 70 is at rest, any suitable means being provided to hold the die heads in correct register for this purpose, such means being shown as forks 34 extending from the respective die heads and engaging the shafts 26. 80

Since for the sequence of operations to be described it is essential that the forming dies 33 of the die heads be moved to extend some little within the plane of the turret, i. e., into the holders 8 to position the cake 85 and for the forming operations, it is essential that at one station of the machine where the pieces of soap are to be fed in, that at least one of the dies be moved back from the plane of the turret enough so that the pieces of soap may be readily inserted 90 so as to be positioned in the holders. Various expedients may be resorted to for this purpose but preferably and as herein shown at the feeding station, designated A, I form 95 the lower die in the die head 24 as a separate element 35 fitted to slide vertically in ways of the die head and acted on by a lever 36 pivoted at 31 to the die head, a projection of said lever beyond said pivot being connected to a rod 38 anchored to the frame base of the machine. The pieces of soap in the rough, to be formed into cakes may be deposited on the die 35 thus lowered at the station A either by hand or by any suitable automatic feed (not shown). As the turret comes to rest, the die heads 23, 24 are moved toward each other under the action of the cam 25 thus moving the pieces of soap fed in and lying in the die cavities 100 of the die 35, up into the then registering compartments 8^a of the then interposed holder 8 and by the co-action of the die 35 with the opposing die 33^a of the upper die holder roughly shaping the cake and causing its peripheral edge to be pressed against the walls of the compartment 8^a. Thereupon as the dies are presently opened as permitted by the receding portions 25^a of the cams 25, the turret is advanced a quarter revolution in a clockwise direction as seen in Fig. 3. The cakes of soap in the compartments of the holder being thus located at the second station designated B of the machine are pressed into shape by one 110 of the sets of the oppositely acting forming dies designated 33^b. At this station I also provide means for perforating the cake with characters to constitute a trade-name or trade-mark or the like and for injecting liq- 115 120 125 130

uid, or relatively fluid soap into such perforations to fill the same. For this purpose I provide perforating dies 39 fitted in one or both of the die heads 23, 24 to slide 5 through apertures formed therefor in the forming dies 33^b. While only one perforating die 39 may be employed to act on a soap cake from one side, I preferably, and as shown, employ oppositely acting perforating dies to act on the cake from both sides, such perforating dies however, as hereinafter explained, being usually formed with diverse characteristics. These perforating dies are actuated by cams 40 fixed 10 on the shafts 26 to periodically press said dies toward each other and into contact with a laterally moving blade at the center of the soap cake as now to be explained. Since it is desirable that these perforating dies be held pressed against such blade for a brief interval I provide springs 41 interposed between the cam 40 and the heads 42 of the dies 39 to provide a degree of resilient pressing action. For introducing 15 the liquid soap at the roots or bases of the perforations thus formed by the action of the perforating dies 39 I provide nozzles 43, 43^a arranged in pairs or sets to inject soap into the respective cakes of a holder, 20 this pair or set of nozzles being supplied from a common tube or flexible conduit 44, and it being understood that the number of nozzles in such set will correspond with the number of compartments in each of the 25 holders 8 as the machine may be constructed. The nozzles 43, 43^a each has a nose 45 adapted to be projected through a hole 46 of the holder 8 into contact with the edge of the soap cake substantially at the median plane thereof. The set of nozzles 43, 43^a are connected to and carried by a slide 47 that is guided to slide endwise on a bar 48 fixed to and extending radially from the fixed central column or shaft 5, the end 30 portion of said bar being provided for this purpose with suitable overhanging bearing clips 49. The conduit 44 is connected with a suitable source of liquid soap supply under pressure this being shown as an overhead tank 50 and suitable means is provided for moving the nozzles outwardly into contact with the soap cakes at the proper intervals. For this purpose an inner curved end 47^a of the slide 47 is held in engagement 35 with an intermittently moving disk 500 by means of a tension spring 51 engaging said slide at one end and having its other end anchored to the central column. The disk 500 has a socket or concave seat 45 formed therein into which the slide end 47^a is adapted to fit and when in this position as held by the spring 51 the nozzles 43 are withdrawn out of the holder 8. For periodically turning the disk 500 so as to 40 operate the slide and press the nozzles out- ward, said disk is fixed on a short shaft 53 journaled in the bar 48 and having rigid and concentric therewith a pinion 54 engageable by a gear 55 fixed at the lower end of a vertical shaft 56. The shaft 56 is 70 journaled and also held from endwise movement by suitable collars in the upper die head 23 and thus the gear 55 partakes of the vertical movements of said die head. Thus the gear 55 is only in mesh with the pinion 75 54 when said die head is lowered, i. e., when the turret is stationary and the forming dies are brought together. The upper end of the shaft 56 is fitted to slide through an extended sleeve of a bevel pinion 57, and is 80 squared or otherwise formed to derive driven movement therefrom, said pinion being journaled in a bracket 58 fitted on the upper shaft 26 and held from rotary or sliding movement by a downward projection 58^a fitting through an opening therefor in the head 23. The pinion 57 is driven by a bevel gear from upper shaft 26, this set of gears in conjunction with the gear pair 54, 55 being so proportioned as to impart one 85 complete rotation to the shaft 53 while the die head 23 is down, i. e., while the gears 54, 55 are in mesh, this being accomplished as shown by a one quarter rotation of the shaft 26. Coöperative with the respective 90 nozzles 43, 43^a, are a set of perforating blades 59, 59^a, these blades being joined at their rear portions in a single web 60, it being understood that this arrangement 95 may be carried out for any number of 100 blades that may be employed for the required number of nozzles, as determined by the number of soap cake holding compartments in each holder 8 to make of such set of blades a single operative unit. The connecting web 60 of these perforating blades is formed with a long transverse slot 61 in which operates a pin 62 carried by a relatively large disk 63 fixed on the lower end of the stub shaft 53 beneath the bar 48. The 105 arrangement of the slot 61 and pin 62 with respect to the cam recess 52 of the disk 500 is such that when the nozzles 43 are retracted by the positioning of the slide end 47^a in such cam recess, at the completion 110 of an operative movement, the slides 59 are in an intermediate position, where they extend substantially to the discharge end of the nozzles 43, the passage of these nozzles being at this end contracted so that said 115 slides fit therein closely and thus serve as valves to prevent the outflow of the liquid soap. At the beginning of an operative movement the nozzles are first moved against the end of the respective soap cakes 120 by the action of the disk 500 on the slide 47 and at the same time the blades 59 are advanced by the action of the pin 62 in the slot 61. This advancing of the blades 59 continues after the movement of the nozzle 125 130

4

stops and the blades are thus pressed through the median plane of the soap cake to a point well beyond the center thereof, and as far as the proposed trade-mark or 5 trade-name is to extend along the cake. Thereupon by the described mechanism the perforating dies 39 are moved in to cut the desired letter or mark perforations in the sides of the cakes, these dies being pressed 10 through until they engage the sides of the blades 59 against which they press with a degree of resilient pressure as imparted by the springs 41. Thereupon, further movement of the pin 62 on disk 63 will retract 15 the blades 59 not only out of the soap cake but also within the nozzles 43, and finally into an enlarged intermediate section 43^b thereof where the discharge end of these nozzles is thus opened, while such nozzles 20 are still held pressed against the end of the soap cake. The liquid soap under pressure from the conduit 44 is now permitted to flow freely into the passages made by the blades 59, 59^a and as the perforating dies 25 39 are at this time moved backward, the cams 40 being for this purpose of relatively short extent, the liquid soap is permitted to fill up into the interstices and cut out spaces made by the perforating dies, this action 30 being facilitated by the suction caused by withdrawal of said dies out of the soap cake, this insuring a complete filling in of such letter or trade-mark spaces with the liquid soap. The final movement of the blades 59 35 under action of the pin 62, just before the pinion 54 is disengaged is again forward so that as the nozzles 43 are then retracted, the ends of said blades will again fill the discharge end of the nozzles and stop the out- 40 flow of soap. It is to be understood that in practice this liquid soap will be preferably of a color contrasting sharply, yet attractively, with that of the body of the cake, thus making at the same time a soap cake 45 of pleasing appearance and one in which the trade-mark or the name of the manufacturer or both will be conspicuously displayed to the user on one or both sides of the cake throughout the period of use of 50 the cake and until it is entirely consumed. It will be understood that the liquid soap thus injected will be rendered only sufficiently fluid so as to be capable of being injected into the soap cake in the manner de- 55 scribed. It may be thus rendered fluid or semi-fluid in any suitable known manner with or without the application of heat, so as to set and become solid to the extent required as soon as necessary after being in- 60 jected into the cut out letter space of the cake.

The cakes of soap in the holder thus perforated and marked are now released by the opening of the dies 33^b and the soap cakes 65 held at their peripheral edges in the holders

8 are transferred by the next movement of the turret to the next station designated C where they are operated on by the finishing dies 33^c carried by the upper and lower die heads 23, 24 respectively. These dies re- 70 shape and finish the soap cakes, and if desired may be so formed as to make the contrasting color of the injected soap stand out more conspicuously. Thereupon upon the release of the cakes by these dies and an other movement of the turret the cakes are brought to the discharge station D. At 75 this station there is an upper die 33^d which when the upper die head 23 is moved down, is projected down far enough to dislodge 80 the soap cakes from the holder 8. At this station there is no lower die and the dislodged soap cakes are thus free to drop on to a suitable conveyer which is shown as a usual endless belt conveyer 64 mounted on 85 a roll 65 journaled to the frame work adapted to carry off the discharged cakes to any desired delivery point. While the machine is herein described as for handling soap cakes this is to be understood as merely an 90 illustrative use and the machine is also adapted and designed for use in pressing and marking with a non-obliteratable trade- 95 mark any relatively soft of moldable material having characteristics more or less like 95 those of ordinary toilet or household soap.

It is also to be understood that while the usual oval form of soap cake is herein shown, that with obvious and easily understood modifications of the dies and immediate operating parts, the machine can equally as well handle any other desired shape of cakes or character of trade-mark or trade-name to be applied thereto. While the several holders 8 are herein shown as formed 100 with only two compartments and the mechanism hence provided to operate on only two cakes at each station, it is to be understood that the invention contemplates a greatly 105 extended range of capacity for these holders when desired, so that each holder may have a large number of compartments to hold for operation a considerable number of cakes at once with of course a corresponding and readily understood multiplication 110 of operating devices, the present smaller number being shown for simplicity of illustration and readier understanding of the principles involved. I desire it also to be understood that the described mechanism 115 with slight modification may if desired be used merely for pressing and shaping soap cakes without the perforating and labeling mechanism. When so used the station designated A may be a feeding and pressing station, the station B a discharge station, the station C a feeding and pressing station, and the station D a discharge station. I therefore desire the present embodiment in 120 these as well as other respects to be consid- 125 13

- ered as illustrative and not restrictive and refer to the appended claims rather than to the foregoing description to indicate the scope of the invention.
5. Having described my invention, what I claim as new and desire to secure by Letters Patent is:
1. A machine of the kind described, comprising press mechanism for molding a cake 10 of soap or the like, means for perforating such cake with distinguishing characteristics, and means for filling the spaces of such perforations with material in a relatively fluid condition including a device for forming a lateral channel intersecting the bases of such perforations. 15
  2. A machine of the kind described, comprising mold for holding cakes of soap or like, mounted and connected for step by step movement, means for producing perforations with distinguishing characteristics in a cake of soap or the like to a substantial depth therein, means for forming a channel through the soap cake transverse of such 25 perforations and intersecting the same, and means for introducing liquid soap into such perforations through said channel including an automatically movable valve controlled nozzle having a range of movement inward 30 to connect with such channel and outward to clear the cake.
  3. A machine of the kind described, comprising press mechanism rotarily movable step by step for molding a cake of soap or 35 the like, means for producing perforations with distinguishing characteristics extending from the surface substantially to a median plane of the cake while held in said press mechanism, means for producing a 40 channel intersecting said perforations at the bases thereof, and means for injecting liquid filling material through said channel to fill said perforations.
  4. A machine of the kind described, comprising means for producing perforations with distinguishing characteristics in a cake 45 of soap or the like from opposite sides thereof to points approaching the median plane of the cake, means for producing a channel 50 extending transversely of such perforations and intersecting the same at the bases thereof, and means for introducing liquid filling material into said channel to fill said perforation spaces.
  5. A machine of the kind described, comprising press mechanism for molding a cake 55 of soap or the like, mounted and connected for step by step rotary movement, means associated therewith for producing perforations with distinguishing characteristics extending from the outside to near a median plane of the soap cake, means for producing a channel in the soap cake transversely of 60 said perforations and intersecting the same at the bases thereof, and means for introducing 65
  - ing liquid soap into said channel to fill said perforations while the cake is still held in said press mechanism.
  6. A machine of the kind described, comprising press mechanism for molding a soap 70 cake approximately to shape, means for transferring the soap cake to a second station, a second press mechanism operative on the soap cake at said second station, means for producing perforations with distinguishing characteristics in the soap cake at said second station, and means for introducing liquid soap to fill said perforations while the cake is held in said second press mechanism. 75
  7. A machine of the kind described, comprising press mechanism for molding a cake of soap or the like, having means associated therewith for producing perforations with distinguishing characteristics extending from the surface of the cake to a substantial depth, with means for introducing liquid soap to fill said perforations, a second press mechanism for molding the cake to finished form, and transfer means for moving the 80 cake from the first named press mechanism to the second named press mechanism. 85
  8. A machine of the kind described, comprising a holder for a soap cake mounted for movement to successive operative stations, 90 said holder formed to leave the soap cake exposed at a side thereof, mechanism at one station for producing ineradicable distinguishing characteristics extending from the surface of the soap cake to a point adjacent 95 a median plane thereof, and a press mechanism at a succeeding station for refinishing the soap cake. 100
  9. A machine of the kind described, comprising rotatable turret bearing, a holder 105 for moldable cakes arranged to leave opposite sides of the cake exposed and mounted for movement to successive stations, press mechanism at one of said stations for molding the cake, mechanism at said station for 110 producing ineradicable distinguishing characteristics in the cake extending from the surface to a point adjacent a median plane thereof while held in said press mechanism, and a second press mechanism at a later 115 station for re-molding and finishing the cake.
  10. A machine of the kind described, comprising a unidirectionally movable carrier bearing, a holder for moldable cakes arranged to leave opposite sides of such cakes exposed, said holder mounted for movement to successive stations, press mechanism at one of said stations for locating and preliminarily molding a cake in said holder, a second press mechanism at a later station for further molding the cake, and mechanism at the last named station for producing ineradicable distinguishing characteristics in the cake extending from the surface to a 120 125 130

substantial depth, and constituting a component part of the material of the cake.

11. A machine of the kind described, comprising a holder for moldable cakes arranged to leave opposite sides of such cakes exposed, said holder mounted for movement to successive stations, press mechanism at one of said stations for locating and preliminarily molding a cake in said holder, a second press mechanism at a later station for further molding the cake, mechanism at the last named station for producing ineradicable distinguishing characteristics in the cake extending from the surface to a substantial depth, and constituting a component part of the material of the cake, a third press mechanism at a still later station for remolding and finishing the cake, and means operative at a fourth station for ejecting the cake from said holder.

12. A machine of the kind described, comprising a holder for moldable cakes arranged to leave opposite sides of such cakes exposed, a turret mounted and connected for intermittent rotary movement and bearing said holder to successive stations, press mechanism at one of said stations for locating and preliminarily molding a cake in said holder, a second press mechanism at a later station for further molding the cake, and mechanism at the last named station for producing ineradicable distinguishing characteristics in the cake extending from the surface to a substantial depth, and constituting a component part of the material of the cake.

13. A machine of the kind described, comprising means for confining a cake of moldable material, means for perforating the cake with perforations to a substantial depth, and means for injecting liquid filling material to fill such perforations, said means consisting in a nozzle mounted for movement up to the cake while so confined, and a perforating blade coöperative with said nozzle and mounted to perforate the cake in a plane transverse of and intersecting said perforations.

14. A machine of the kind described, comprising means for confining a cake of moldable material, means for perforating the cake with perforations to a substantial depth, and means for injecting liquid filling material to fill such perforations, said means consisting in a nozzle mounted for movement up to the cake while so confined, and a perforating blade mounted and connected for movement in timed relation to the movements of said nozzle to perforate the cake in a direction transverse of said first named perforations and intersecting the same, said perforating blade fitted in said nozzle and coöperative therewith to constitute a valve therefor to control the flow of filling material therefrom.

15. In a machine of the kind described, press mechanism for confining a cake of soap

from opposite sides thereof, means for perforating said cake from opposite sides to a point adjacent a median plane of the cake with distinguishing characteristics, and means for filling said perforations consisting in a nozzle mounted and connected for movement up to and away from the cake, and a perforating blade coöperative with said nozzle and connected to be moved for perforating the cake in a median plane thereof, transverse of the first named perforations to connect therewith.

16. In a machine of the kind described, press mechanism for confining a cake of soap from opposite sides thereof, means for perforating said cake from opposite sides to a point adjacent a median plane of the cake with distinguishing characteristics, and means for filling said perforations consisting in a nozzle mounted and connected for movement up to and away from the cake, and a perforating blade coöperative with said nozzle and connected to be moved for perforating the cake in a median plane thereof, transverse of the first named perforations to connect therewith, said blade having a slidable fitting through said nozzle and serving as a valve to control the flow of liquid filling material therefrom.

17. In a machine of the kind described, a pair of dies mounted for opposing action to confine a soap cake therebetween, perforating dies slidably fitted through said confining dies and formed to produce perforations in the cake confined of a distinguishing character and extending to near the median plane of the cake, and means for injecting liquid material to fill such perforations consisting in a nozzle having connection with a source of liquid material under pressure, and a perforating blade associated with said nozzle and movable to pass through the soap cake intersecting the first named perforations.

18. In a machine of the kind described, a pair of dies mounted for opposing action to confine a soap cake therebetween, perforating dies slidably fitted through said confining dies and formed to produce perforations in the cake confined of a distinguishing character and extending to near the median plane of the cake, and means for injecting liquid material to fill such perforations consisting in a nozzle having connection with a source of liquid material under pressure, and a perforating blade associated with said nozzle and movable to pass through the soap cake intersecting the first named perforations, said nozzle and said perforating blade having operative connections intermittently connectable automatically as said confining dies are brought together.

19. A machine of the kind described, comprising a turret mounted and having operative connections to receive intermittent ro-

tary movement, a plurality of holders for cakes of soap or the like carried by said turret and presenting a side of the cakes exposed, means for molding the cakes in said 5 holders, and means operative at one station of said turret for producing ineradicable distinguishing characteristics in the soap cake, said means consisting in a perforating die mounted and connected to be moved for 10 perforating the soap cake to a substantial depth and a nozzle having a perforating blade associated therewith connected for in- termittent movement whereby said blade first perforates the cake in a direction transverse of the first named perforations and intersecting the same, and thereafter said nozzle is moved to deliver liquid soap to fill said perforations, said nozzle having a connection to a source of liquid soap under pressure. 15

In testimony whereof, I have signed my 20 name to this specification.

VICTOR F. CARL.
